TOWEL DISPENSER

Jay C. Perrin, Los Angeles, Calif., assignor to
Towlsaver, Inc., a corporation of California

Application December 17, 1934, Serial No. 757,778

16 Claims. (Cl. 242—55.5)

This invention is of the same general character and form and is for the same purpose as the invention disclosed in Letters Patent No. 1,913,722, granted to me on June 13, 1933, but embodies several major and minor improvements which will appear as the description of the present invention progresses.

Briefly, this invention contemplates the provision of a simple, efficient and durable mechanism including a suitable case arranged to rotatably and detachably support a roll of towel paper in such a manner in the case that substitution of inferior or the other grades or kinds of paper may not ordinarily be made without detection or tampering with the mechanism, thereby insuring uniformity of quality of the paper used in the dispenser.

Another object is to provide accurate means for gripping, measuring and dispensing uniform sections of towel paper and including a couple of dispensing rollers at least one of which is rotated independently of the paper roll and to exactly the same extent in all dispensing operations, together with means associated therewith and under manual control for releasing and instituting movement of the dispensing rolls and automatically operable for stopping the operation thereof when a predetermined length of paper has been dispensed for use.

Other objects include: the provision of means to prevent the backward rotation of the paper roll when the mechanism is at rest; means for accurately centering the paper in the case and the prevention of longitudinal movement of the paper roll, and still other features which I will describe hereinafter.

In the accompanying drawings I have shown a preferred form of mechanism for the purpose described, subject however, to modification within the scope of the appended claims without departing from the spirit of my invention.

In said drawings:

Fig. 1 is a front elevation of the assembled dispenser partly broken in section so as to show the operating elements of the mechanism;

Fig. 2 is a sectional elevation of the same on line 2—2 of Fig. 1;

Fig. 3 is a sectional elevation on line 3—3 of Fig. 1;

Fig. 4 is a fragmentary section on line 4—4 of Fig. 3, showing a detent associated with one of the paper dispensing gears;

Fig. 5 is a sectional elevation on line 5—5 of Fig. 1;

Fig. 6 is a sectional plan on line 6—6 of Fig. 3;

Fig. 7 is a sectional elevation on line 7—7 of Fig. 1;

Fig. 8 is a fragmentary section of the operating means on line 8—8 of Fig. 7.

My dispensing means includes a two piece case comprising a case C and a cover C' hinged together at the front of the case as by means of a pair of hinges 1, 1. Said hinges are attached to the lower edge portion of the front wall 2 of member C' and to the bottom 3 of member C. It will be observed that member C has parallel ends 4 and 5 and a back 6, while member C' has ends 7 and 8 and the front wall 2 is continued upwardly and backwardly over the edges of the ends 4 and 5 of member C so as to completely enclose the mechanism within the case. Ends 7 and 8 of member C' overlie the ends 4 and 5 of member C, respectively. Member C' may be suitably secured to member C as by means of a latch 9 adapted to engage a member 10 attached to the back 6 of member C.

Thus, the case C is open at the top and front so as to permit the ready attachment or removal of a roll of towel paper R.

At longitudinally opposite positions on the case C supporting members 11 and 12 of different form are permanently secured to the ends 4 and 5, respectively. Member 12 has laterally formed flanges 14, 14, which are suitably affixed to the end 5, and a wall 13 spaced from end 5 of case C. Said member also has a semi-circular bearing portion 15 at the bottom of a slot 16 which is open at its upper end for receiving a trunnion 17 carried by the paper roll R at one of its ends.

It will be noted that the bearing 15 is of but the thickness of the metal plate of which the member 12 is formed and said bearing is in a plane but slightly spaced from the plane of its associated flange, thereby providing a recess 18 between the bearing and the inner side of the end 5. Member 11, however, is differently formed, of spring wire and is provided with a V shaped bearing portion 19, the apex of which is axially aligned with the roll R, and has upper and lower end portions 20 and 21 which overlie the outer side of end 4 of case C. The lower end 21 is fixedly held by means of a plate 22 attached to the end of case C. The portion 19 of member 11 is threaded through slots 23, 23 above and below a rib 24 so as to prevent the complete retraction of said member.

The paper rolls R are usually formed with a stiff hollow paper core 25, in one end of which I provide a metal trunnion 17 which serves to rotatably support the paper roll R on the member 55

12. Said trunnion is of cup form with a cylindrical portion 26 adapted to be frictionally or otherwise held in the core 25 and has a flange 27 at its outer and open end, as shown in Fig. 1.

5 At the junction of the cylindrical body portion 26 with the flange 27 a slightly enlarged annular portion 27' may be provided for rotatably engaging the semi-circular bearing 15. When the trunnion is thus positioned in the supporting member 12 the flange 27 thereof will rest in the recess 18 at the rear of the bearing 15, thereby preventing the longitudinal movement of the roll R. Member 11 is so formed and tensioned that the portion 19 will engage the adjacent end of core 25 and thus support the roll R detachably in the case. The roll R is inserted by moving it downwardly so that member 17 will rest in bearing 15 and the member 11 will yield and finally seat the portion 19 thereof in the end 20 of core 25.

In the front portion and at the bottom of the case member C I provide a couple of parallel dispensing rollers 28 and 29 by means of and between which the paper P from the roll R is adapted to be dispensed in uniform lengths at each operation of the machine. Said rollers are preferably made of wood but may be formed of other suitable material. Roller 28 is rotatably supported on the ends 4 and 5 of case C by means 30 of trunnions 30 which are firmly held in and extend from the opposite ends thereof and through suitable perforations in the ends of the case C. Said roller 28 is of uniform diameter throughout its length and is adapted to receive 35 and grip the paper P from the roll R, as shown in Fig. 5.

Roller 29 is yieldably mounted relative to roller 28 and has trunnions 31 which extend through slots 32 in the ends 4 and 5 of the case and are 40 resiliently connected with the trunnions 30 of roller 28 by means of tension springs 33, 33. Roller 29 has a central section 34 which engages the paper P and reduced end sections 35, 35, and said central section 34 serves to centralize the 45 paper P in the case and to prevent the edges thereof from creeping longitudinally on the rollers 28 and 29.

Roller 28 has a ferrule 36 at one end tightly pressed on to a slightly reduced end portion 50 thereof, to which is suitably attached a pinion 37. Said pinion operatively engages a spur gear 38 which is fixed to an operating spindle 39 formed on or attached to an operating crank 40. Said spindle is journaled in the end 5 of the case C and carries externally of the end 5 a combined cam and locking member 41 which cooperates with a control lever 42 pivotally held at 43 on the end 5 of the case and adapted to be manually operated for releasing the spindle 60 39 for rotation, but is automatically effective for stopping the rotation thereof when a predetermined length of paper has been dispensed from the roll R.

Member 41 is generally circular in configuration but has a projecting lug 44 on the periphery thereof which is engageable with a lug 45 on member 42, as shown in Fig. 7, for stopping the rotation of the spindle 39 and associated parts at the conclusion of a dispensing operation.

70 Member 42 has a handle 46 which, when the mechanism is at rest, normally occupies a position as shown in full lines in Fig. 7 and is operable manually by elevating the handle to the position shown in broken lines in Fig. 7, for 75 moving the lug 45 out of the path of lug 44 on

member 41. Thereafter, as handle 40 is rotated in a clockwise direction, as shown in Fig. 7, the lug 44 thereon will engage a second lug 47 on lever 42, after lug 44 has cleared lug 45, and cause a retraction of lever 42 to normal position 5 with the edge of lug 45 engaging the concentric portion of the periphery of member 41 and in readiness to engage and stop the further rotation of the handle 40 and the dispensing rollers 28 and 29.

The sections of paper P dispensed from the machine are preferably of greater length than width, and the length of said sections is determined by the ratio of gears 37 and 38. As shown herein, gear 38 makes one complete revolution 13 at each operation of the machine while gear 37 may make two or more revolutions, depending upon the diameter of roller 28 and the gear ratio between the operating spindle and said roller. In all cases, however, roller 28 is rotated to exactly the same extent at each operation of the machine and consequently measures and dispenses uniform lengths of paper P in successive operations. It will be noted that in this machine, the operating member being attached to the dispensing means, the gradually decreasing size of the roll R does not correspondingly vary the length of the paper section dispensed therefrom, as in other machines.

The end of the paper from the roll R is preferably loosened from the roll and moved back and under the roll over roller 28 and thence between the rollers 28 and 29, and downwardly through an elongated aperture 48 in the bottom of the case C. Preferably the material cut away 35 from the bottom of the case C to form the aperture 48 is bent downwardly on an incline, as shown in Fig. 5, to form a cutting blade 49 having a serrated cutting edge. (See Fig. 1.) It should be noted that portions of the bottom 3 40 are bent upwardly to define fingers 49' as shown in Figs. 1 and 5. These fingers engage in grooves 35' formed at the junctures of sections 34 and 35 of the roller 29, the sides and ends of said fingers being in substantial engagement with or 45 lying close to the walls of said grooves. This arrangement prevents the paper from creeping under the rollers and insures a direct feed of paper from between the rollers 28 and 29 out through the aperture 48.

When the paper is thus threaded between the rollers 28 and 29 the roll R is prevented from backward rotation by means of a detent 50 which is pivotally held at 51 on the end 5 of case C and engages the teeth of gear 38 at its free end, as 55 shown in Fig. 3. Detent 50 has a pair of friction plates 52, 52 attached thereto and overlying the sides of gear 38, for the dislodgment of the detent and for other purposes which appear hereinafter.

In operation, a roll R of paper carrying the trunnion 17 at one of its ends is inserted in the open case by moving the same downwardly until the annular portion 27' of the trunnion seats in the bearing 15 and the opposite end of the roll R seats on portion 19 of member 11. The end of the paper is then threaded between the rollers 28 and 29, as hereinbefore described and upon the operation of lever 46 and handle 40, dispenses a measured strip of paper through aperture 48.

When a piece of towel paper is removed from the machine the lever 42 is raised until the lugs 44 and 45 are disengaged and crank 40 is then turned in a clockwise direction as seen in Fig. 7. Immediately after the disengagement of lugs 44 75

and 45, the lug 44 on member 41 will engage lug 47 on member 42 and retract lug 44 into the path of lug 45, so that it will be impossible to rotate the crank 40 more than a single revolution at each operation. Moreover, the automatic operation of lever 46 prevents more than a suitable length of paper P from being dispensed in one operation, and no manual attention or operation is necessary to effect this economy.

10 The bearings 11 and 12 which support the roll R are so formed and positioned that any trunnion without the flanges 21, or other makeshift devices, could not be effective for operatively supporting the roll R. It would therefore, be 15 difficult if not quite impossible to rotatively mount other rolls of paper than those supplied, for use in this particular machine in a satisfactory manner. The annular portion 27' and the recess 18 are of such depth that ample clearance is provided for the roll R to prevent binding of the paper on the case ends or other parts of the machine. Said annular portion 27' being larger 20 in diameter than the body 26 serve to limit the inward thrust of the trunnion into the tubular core 25 of the roll R.

As shown in Figs. 1 and 6, a strip 18' is attached to the end 5 of the case C opposite and adapted to engage the flange 27 of the trunnion 17 for preventing longitudinal movement of the 30 roll in the case, the tension of the member 11 serving to keep the roll R to the right, as seen in Fig. 1, and the flange 27 of trunnion 17 being confined between the member 18' and the central portion of member 12.

35 Preferably member 12 is of sufficient size as to enclose the detent 50 and the upper portion of gear 38, thereby preventing damage to the detent when the case is opened to insert a roll of paper or for other purposes. It will be understood that a too rapid rotation of the operating lever 40 will tend to unwind a surplus amount of paper from roll R, hence the detent 50, by reason of the frictional engagement of plates 52 with the sides of gear 38, together with the friction 40 of member 11 on the core of the roll, serves to prevent an overmovement of the roll.

The friction plates 52, however, serve a more important purpose in that they prevent the dislodgment of the detent 50 from gear 38 and 50 renders the operation of said gear silent. In operation, as handle 40 is rotated forwardly as in a dispensing operation the detent 50 is lifted out of engagement with the teeth of gear 38 by means of the friction of plates 52 on the sides 55 of the gear and the detent remains in an elevated and disengaged position so long as the handle is rotated, thereby preventing the clicking noise which is made by a pawl and ratchet. If, however, the handle is rotated backwardly, the friction 60 of plates 52 on gear 38 causes the detent to immediately engage the teeth of the gear and the mechanism is locked against reverse movement.

It is also highly important to prevent the lateral creeping of the paper on the rollers 28 and 29 which might occur when a surplus amount 65 of paper has been unwound from the roll R or under other conditions. The combined effect of the central enlarged portion 34 of roller 29 and the tension of member 11 which serves to hold the roll R at its right hand extreme of movement as shown in Fig. 1 and applies friction on the end of core 25, is to remove the possibility of the paper creeping as it is unwound from the roll.

70 The form and arrangement of the bearing

member 11 is such that said member may not be completely removed from the case and as the roll R is moved downwardly into operating position the central V shaped portion 19 will yield and finally settle into position in the end of the core 25 when the trunnion 17 is seated in its bearing 15. In like manner as the core of the roll R is removed, or the roll of paper, member 11 will yield as the roll is moved upwardly. Thus, with the differently formed bearing members 11 10 and 12 and the associated trunnion 17, makeshift devices for supporting a roll of paper are ineffective.

What I claim, is:

1. A towel dispenser comprising: a case adapted 15 to enclose and rotatably support a roll of towel material, a stationary bearing attached to a wall of said case and having a bearing portion spaced from said wall, a yieldable bearing attached to an opposite wall of said case and having a bearing 20 portion engageable with an end of said roll of material, and means in said roll of material adapted to be supported in said stationary bearing for operatively supporting said roll of material, said means including an annular portion 25 forming a trunnion and engaging said stationary bearing and a flange on said trunnion intermediate said bearing and the adjacent wall of said case, for preventing the displacement of said roll of material from the stationary bearing. 30

2. A towel dispenser comprising: a case, and means for rotatably supporting a roll of towel material therein including, a plate secured to a wall of said case and provided with a bearing open at its periphery, a yieldable bearing member 35 attached to an opposite wall of said case and having a portion axially aligned with said bearing, and means insertible in said roll of material and adapted to rotatably engage said stationary bearing for operatively supporting the roll of material, said yieldable bearing member embodying a tensioned rod having oppositely inclined portions engageable with an end of the roll of material, whereby when the roll of material is moved into and from operative position, said portion will 40 flex so as to seat in and disengage itself from the roll of material. 45

3. A towel dispenser comprising: a case adapted to enclose and support a roll of towel material, and means for rotatably supporting said roll 50 of material including an axially disposed flanged trunnion attachable to one of the ends of the roll of material, a supporting member affixed to and spaced from the adjacent side of the case and forming a bearing therefor, the flange of said 55 trunnion being held between said case and a portion of said supporting member, and a yieldable member carried by the opposite side of said case and insertible in the end of said roll of material.

4. A towel dispenser comprising: a case, bearings permanently attached to opposite portions of said case, one of said bearings being stationary and formed with a base attached to a wall of the case and having an opening offset from the plane of its base so as to provide a recess outwardly of 60 the bearing portion, a trunnion attachable to an end of a roll of towel material and having a portion rotatably engaging said bearing and a flange seated in said recess, said other bearing being yieldable and insertible in the adjacent end of 65 said roll.

5. A towel dispenser comprising: a case, means for rotatably supporting a roll of towel material therein, a rotatable operating crank, a dispenser roller gear connected with said crank, means for 70

limiting the movement of said crank so as to dispense uniform lengths of material at each operation of the crank, and a detent associated with said crank gear and including a friction element attached to said detent and overlying a side of said gear, for preventing the dislodgment of said detent.

6. A towel dispenser comprising: a case, means for rotatably supporting a roll of towel material in said case, a rotatable operating crank, a pair of dispensing rollers between which the paper from said roll is fed outwardly from said case, a gear associated with said crank, a gear associated with one of said rollers and operatively connected with the gear on said crank, a detent operatively engaging the teeth of said crank gear for preventing the backward rotation of the crank and roll, and friction plates carried on said detent and engaging the sides of said crank gear, whereby when the crank is rotated forwardly said detent will become disengaged from said gear and upon the initial backward movement of said crank said detent will become engaged with said gear, by reason of the friction of said plates.

7. A towel dispenser comprising: a case having spaced side walls, means for rotatably supporting a roll of towel material therein including a bearing plate secured to one of said walls and spaced therefrom, a trunnion held in the adjacent end of said roll of material and journalled in said plate and provided with a flange confined between said plate and the wall to which it is secured for preventing the longitudinal movement of said roll, and yieldable means carried by the other side wall and engaging said roll.

8. A towel dispenser comprising: a case having spaced side walls, means for rotatably supporting a roll of towel material therein including a bearing plate secured to one of said walls and spaced therefrom, a trunnion held in the adjacent end of said roll of material and journalled in said plate and provided with a flange confined between said plate and the wall to which it is secured for preventing the longitudinal movement of said roll, yieldable means carried by the other side wall and engaging said roll, and manually operable means for rotating said roll for issuing paper therefrom for use.

9. A towel dispenser comprising: a case having spaced side walls, means for rotatably supporting a roll of towel material therein including a bearing plate secured to one of said walls and spaced therefrom, a trunnion held in the adjacent end of said roll of material and journalled in said plate and provided with a flange confined between said plate and the wall to which it is secured for preventing the longitudinal movement of said roll, yieldable means carried by the other side wall and engaging said roll, and manually operable means for rotating said roll for issuing paper therefrom for use, said manually operable means including a pair of dispensing rollers one of which is substantially shorter than the other and between which the paper is issued from the dispenser.

10. A towel dispenser comprising: a case having spaced side walls, means for rotatably supporting a roll of towel material therein including a bearing plate secured to one of said walls and spaced therefrom, a trunnion held in the adjacent end of said roll of material and journalled in said plate and provided with a flange confined between said plate and the wall to which it is secured for preventing the longitudinal movement of said roll, yieldable means carried by the other side wall and engaging said roll, and manually

operable means for rotating said roll for issuing paper therefrom for use, said manually operable means including a pair of dispensing rollers substantially spaced from the periphery of said roll between which the paper is issued from the dispenser for use.

11. A towel dispenser comprising: a case having spaced side walls, means for rotatably supporting a roll of towel material therein including a bearing plate secured to one of said walls and spaced therefrom, a trunnion held in the adjacent end of said roll of material and journalled in said plate and provided with a flange confined between said plate and the wall to which it is secured for preventing the longitudinal movement of said roll, yieldable means carried by the other side wall and engaging said roll, manually operable means for rotating said roll for issuing paper therefrom for use, said manually operable means including a pair of dispensing rollers substantially spaced from the periphery of said roll between which the paper is issued from the dispenser for use, and means for controlling the operation of said manually operable means and said dispensing rollers for issuing strips of paper of uniform length.

12. A towel dispenser comprising: a case having spaced side walls, means for rotatably supporting a roll of towel material therein including a plate secured to and spaced from one of said walls and having a bearing slot therein open at the upper end of said plate, a member secured to and coaxial with said roll adapted to seat in said bearing and having a portion confined between said plate and its supporting wall for preventing longitudinal movement of said roll, and a yieldable support for the other end of said roll carried by said other wall, whereby said roll may be detachably held in operative position.

13. A towel dispenser comprising: a case having spaced side walls, means for rotatably supporting a roll of towel material therein including a plate secured to and spaced from one of said walls and having a bearing slot therein open at the upper end of said plate, a member secured to and coaxial with said roll adapted to seat in said bearing and having a portion confined between said plate and its supporting wall for preventing longitudinal movement of said roll, a yieldable support for the other end of said roll carried by said other wall, whereby said roll may be detachably held in operative position, and means for dispensing strips of paper from said roll.

14. A towel dispenser comprising: a case having spaced side walls, means for rotatably supporting a roll of towel material therein including a plate secured to and spaced from one of said walls and having a bearing slot therein open at the upper end of said plate, a member secured to and coaxial with said roll adapted to seat in said bearing and having a portion confined between said plate and its supporting wall for preventing longitudinal movement of said roll, a yieldable support for the other end of said roll carried by said other wall, whereby said roll may be detachably held in operative position, means for dispensing strips of paper from said roll, said dispensing means including a manually operable crank, and a pair of dispensing rollers operable by said crank between which the paper is issued from said dispenser.

15. A roll of towel material for use in a towel dispenser, having provision at an end thereof for rotatably supporting said end, and a bearing member having a portion permanently fixed to

and extending axially outwardly from the other end of the roll and having a flange spaced outwardly from and being parallel with said other end, and a circumferential bearing portion exposed between said roll and said flange.

16. In a towel dispenser, a roll of towel material including a tubular core having one end fully open, and a trunnion having a portion per-

manently fixed to the other end of said core and a projecting portion including a flange spaced outwardly from and being substantially parallel with said other end, said projecting portion defining a bearing between the flange and adjacent the end of the roll.

JAY C. PERRIN.
